MACHINE FOR CLEANING OR HACKLING FIBER.

1,418,493.

Specification of Letters Patent. Patented June 6, 1922.

Application filed February 9, 1921. Serial No. 443,598.

To all whom it may concern:

Be it known that we, JAMES B. STENGER, EDMUND McCAFFRAY, and CHARLES E. CYLER, citizens of the United States, and residing at Baltimore city, State of Maryland, have invented certain new and useful Improvements in Machines for Cleaning or Hackling Fiber, of which the following is a specification.

10 The present invention relates to machines for combing, scraping or hackling fibrous materials and particularly to machines for hackling broom corn in which it is desired to scrape the seeds and refuse from the ends 15 of the leaves, to cut the stock to the proper length, and to comb or hackle the butt end of the corn before it passes from the machine. It is particularly desirable that during the hackling and sawing of the corn 20 that it be firmly held against movement while at the same time the fibers should not be gripped or pinched in such manner as to become bruised or broken so that the quality of the product is reduced in grade. 25 A particular object of the present invention is to provide a novel means for feeding the corn to the hackling or combing devices and to hold it, while being combed or hackled, by pneumatic pressure so that while 30 it is firmly held it can not be bruised or broken and thereby weakened. A hackling machine having the improved fiber holding means will be fully disclosed in the following description and in the accompanying drawings in which:

Fig. 1 is a side elevation of the hackling machine;

Fig. 2 is an end elevation of the machine as viewed from the left;

40 Fig. 3 is a top view of the machine;

Fig. 4 is a section on line 4—4 of Figure 3; and

Fig. 5 is a section on line 5—5 of Figure 1, to a larger scale.

45 Rotatably supported in the frame of the machine are two star wheels 10 and 11 respectively, the spaced serrated edges of which are adapted to engage wisps of broom corn or bunches of fibrous material of other kinds and to feed it through the machine in the manner hereinafter to be described. These star wheels are parallel and overlapping. They are adapted to rotate simul-

taneously in the same direction and at the same speed, having pulleys 12 and 13 respectively connected thereto, an endless belt 14 passing over these pulleys and tying the star wheels for simultaneous rotation.

55 Mounted on the shaft supporting star wheel 10 is a second pulley 15 and a belt 16 connects this pulley with a pulley 17 mounted on a shaft 18 which is driven from power shaft 19 through a worm 20 and worm wheel 21. Also mounted on shaft 19 is a hackling or combing drum 22 of any ordinary or usual 60 type but which is preferably of the type illustrated, comprising a cylindrical drum provided with a plurality of radially projecting spikes 23. The axis of the hackling drum 22 is in substantially the same horizontal plane as the top of the star wheel. Arranged parallel to shaft 19 is a short shaft 24 connected by means of a belt 25 to the power shaft for simultaneous rotation therewith, and this shaft supports a second 65 hackling drum 26 positioned opposite the top of the star wheel 11. This hackling drum may be similar to the drum 22 or it 70 may be different, if desired. A circular saw 27 having its blade in a plane parallel to the planes of the star wheels 10 and 11 is 75 operatively connected by means of pulley wheels and belts to shaft 18.

80 Mounted vertically above each of the star wheels on shafts parallel to the shafts supporting the star wheels are wheels 28 and 29 respectively which are freely rotatable and which have pneumatic tires 30 and 31 respectively, mounted on their peripheries. The pneumatic tires are partially inflated 85 and are adapted to bear on fibrous materials arranged transversely of the star wheels, as clearly shown in Figure 5, to hold the materials firmly against the star wheel as it passes the hackling drum. These tires 90 accommodate themselves to the shape and size of the fibers supplied to the machine and, while pressing firmly against the fibers and preventing their movement, at the same time have no crushing or bruising tendency.

95 At the right hand end of the machine is located a platform 32 which is a feeding platform, the wisps of corn fiber being fed from this platform in between the teeth of the star wheel 10 and being carried by this 100 star wheel toward the first hackling drum.

The wisps are arranged with the butt end on the side toward the circular saw and are positioned so that the saw will cut off the proper length of the butt end. In passing 5 from the feeding platform 32 up to the point where the partially inflated tire 30 grips the fibers they are prevented from falling from the star wheel by the curved guard 33. Passing from under the guard the wisps of corn 10 are immediately pinched or pressed against the star wheel by the tire 30 and are held by this tire until the ends of the fibers have been hackled or combed by the first hackling drum and the butt ends has been cut by the 15 circular saw.

After having been freed by the tire 30 the wisps of corn are carried downward by the star wheel toward the second star wheel, a guard 34 being provided to prevent 20 placement of the wisps, and a stripping device 35 supported upon the frame being provided for removing the wisps of corn from the first star wheel. This stripping device comprises a support 36 (Fig. 4) and two 25 parallel wires or rods 37, the ends of which lie in grooves 38 in the cylindrical surface of the star wheel.

After being stripped from the first star wheel, the wisps of corn are engaged by the 30 teeth of the second star wheel and pass upwardly toward the second hackling drum. This hackling drum is adapted to comb or hackle the hurl or butt ends of the corn wisps and after it has been completed the 35 corn is carried downwardly and is stripped from the second star wheel 11 by a second stripping device comprising a support 39 mounted on the frame and two wires or rods 40 which enter circular grooves in the periphery of the star wheel. Guards 41 and 42 are provided to prevent the wisps of corn 45 from falling from the star wheels prematurely. After being stripped the corn falls upon an endless belt 43 which will convey the same to a bin or collecting receptacle.

By utilizing means for holding the fibers by pneumatic pressure alone as the hackling operation is carried out, the quality of the products is greatly improved. The various 50 fibers are firmly held and positively prevented from movement during the hackling operation yet they can not be bruised by the pneumatic gripping device. Furthermore this device will adapt itself to fibers or wisps 55 of fiber such as broom corn which vary

greatly in size and will hold a small fiber or wisp as readily as a large one.

The invention may be embodied in different forms and is not limited in its scope to the exact form above described and illustrated in the drawings. The scope of the invention is clearly pointed out in the appended claims.

Having thus described the invention what is claimed as new and desired to be secured 65 by Letters Patent is:

1. In a machine of the class described, in combination, means for combing fibrous materials, and means for feeding such materials past the combing means including a rotatable wheel member the tread portion of which is adapted to be pressed by pneumatic pressure against the fiber to hold the same, and a second rotatable wheel in the same plane to support the fiber against movement 70 away from said first wheel.

2. In a machine of the class described, in combination, means for combing fibrous materials, and means for feeding such materials past the combing means including two contacting wheels one of which has a pneumatic tire mounted thereon the tread of the tire being adapted to bear on the fiber as it passes the combing means to hold the same.

3. In a machine of the class described, in combination, means for combing fibrous materials, and means for feeding such materials past the combing means including a rotatable wheel for supporting the fiber and carrying it past the combing means, and a second wheel in the same plane and provided with a pneumatic tire adapted to bear on the fiber carried by the first wheel, as it passes the combing means, to hold the same.

4. In a machine of the class described, in combination, a relatively stationary means for combing fibrous materials, and means for feeding such materials past the combing means including two rotatable wheels arranged in the same plane and adapted to 95 cooperate to hold the fiber between them one of said wheels having a tire of yielding material to firmly grip the fiber without injuring the same.

In testimony whereof we affix our signatures.

JAMES B. STENGER.
